UNITED STATES PATENT OFFICE.

SAMUEL ARTHUR WELLS, OF GRIMPASS, IDAHO.

PADLOCK.

1,314,775.

Specification of Letters Patent. Patented Sept. 2, 1919.

Application filed December 3, 1914. Serial No. 875,346.

To all whom it may concern:

Be it known that I, SAMUEL ARTHUR WELLS, a citizen of the United States, residing at Grimpass, in the county of Boise and State of Idaho, have invented certain new and useful Improvements in Padlocks, of which the following is a specification.

This invention relates to combination locks, and more particularly to that class of locks that are commonly known as keyless padlocks.

The object of this invention is to provide a padlock that has a pair of rotatable tumblers that facilitate the opening of the lock, 15 said tumblers having simple and effective means whereby the combination may be quickly and readily changed when desired.

Another object of this invention is to provide a keyless padlock that comprises essentially two sections, one of which carrying a pair of tumblers that are rotated in such a manner so as to be able to take the sections apart.

A still further object of this invention is 25 the production of a device of the kind above described, that is simple in construction, efficient in operation and can be manufactured for the minimum amount.

With these and other objects in view, this 30 invention consists of certain novel constructions, combinations and arrangements of parts as will be hereinafter fully described and claimed.

In the accompanying drawings:—

35 Figure 1 is a view in elevation of the improved padlock with the locking means therefor shown in section.

Fig. 2 is an enlarged view in elevation of a portion of one of the locking elements in 40 engagement with the shackle element.

Fig. 3 is a section taken on line 3—3 of Fig. 1.

Fig. 4 is a section taken on line 4—4 of Fig. 1.

45 This padlock comprises essentially two sections, and for the sake of identification the numeral 10 represents the primary section and the numeral 11 the auxiliary section. The primary section 10 consists essentially of a loop having at the ends thereof enlargements 12. It will be seen by referring to Fig. 1 that the section 10 is hollow, and adjacent the end of each of the enlargements 12 is formed a circularly arranged 50 groove 13 that has communicating therewith a slot 14.

The auxiliary member 11 comprises a loop, and has at each of the ends of the same an externally threaded portion on which is threaded an internally threaded collar 15 60 that has an opening in the end thereof. As is shown in Fig. 1, this auxiliary section 11 is hollow, and the openings in the collars 15 communicate with the hollow portion of the auxiliary section. To insure the retaining 65 of these collars 15 upon the ends of the loop of the auxiliary section 11, pins or other means 16 are passed through the collars and through the walls of the section 11, and thereby prevent the rotation of the collars 70 upon the said sections.

A pair of loosely retained shackle legs 17 having circumferential enlargements 18 thereon are carried by the auxiliary section 11, and have intermediate the length thereof 75 projections 19, and adjacent one end thereof projections 20. Rotatably mounted upon the shackle legs 17 between the projections 19 and 20 are rotatable tumblers 21, each having an opening formed centrally thereof, 80 and running from said opening a plurality of cut-out portions 22, the tumblers also being provided with notches 23 on the outer periphery thereof, and corresponding marks being placed upon the collars 15, the tumblers 85 can be brought to the desired position.

The operation of this device is as follows. To establish a combination the tumblers 21 are positioned upon the shackle legs 17 in such a manner that one of the several cut-out portions 22 is in engagement with one of the intermediately disposed projections 19, and the shackle legs are placed in the primary section 10, of course, the projections 20 formed thereon passing into the 95 same by means of the slots 14, and when the same reach the circularly disposed grooves 13, the tumblers 21 being secured from rotation on the shackle legs 17 when one of the projections 19 is positioned in one of 100 the cut out portions 22 are rotated, thus bringing the projections 20 out of alinement with the slots 14, and of course prevent the removal of the sections 10 and 11 from one another. When it is wished to remove the sections from one another, the tumblers are rotated until the desired combination is secured, thus bringing the projections 20 in alinement with the slots 14 and the sections can be easily withdrawn. 105

When it is wished to change the combination all that is necessary is to move the tum-

blers on the shackle legs 17 to such a distance that the projections 19 are out of engagement with the cut-out portions 22 and rotate the tumblers upon the shackle legs 5 and place the projections 19 in one of the several cut-out portions in the tumblers.

It will be seen by careful reference to Fig. 1 that the ends of the projections 19 are beveled so as to engage the inclined faces 10 of the cut-out portions 22 formed in the tumblers. Therefore when one of the projections is positioned in any one of the cut-out portions 22 the beveled face of the projection will engage the inclined face of the cut-out portion and a frictional engagement thus made. By this frictional engagement the likelihood of the projection being accidentally removed from the cut-out is obviated.

20 It is obvious that minor changes may be made in the form and construction of this invention without departing from the material parts thereof. It is therefore not wished to confine the invention to the exact form 25 herein shown and described, but it is wished to include all such as properly come within the scope of the claims.

I claim—

1. A lock comprising a primary and an 30 auxiliary section, said auxiliary section having a pair of shackle legs carried thereby for insertion in said primary section, tumblers on said shackle legs, means on said shackle legs to retain said tumblers in different 35 positions on the same and a second means on said shackle legs to detachably retain certain ends thereof in said primary section.

Copies of this patent may be obtained for five cents each, by addressing the "Commissioner of Patents, Washington, D. C."

2. A lock comprising a pair of sections, one of said sections having a pair of shackle legs, each of said shackle legs provided with 40 projections formed intermediate the length thereof, tumblers on said shackle legs having cut-out portions adjacent said shackle legs to receive said projections on said shackle legs, whereby the position of said tumblers 45 on said shackle legs may be changed, and means on one end of said shackle legs for detachably retaining the same in the section other than the one that carries the same.

3. A lock comprising a pair of sections, 50 one of said sections having a pair of shackle legs carried thereby, means on said shackle legs for detachably retaining the same in the section other than the one that carries the same, each of said shackle legs carrying a 55 projection thereon intermediate the length thereof, said projections having the ends 60 of the same beveled, a pair of tumblers on said shackle legs in proximity with said projections, said tumblers having a plurality of cut-out portions in the path of said projections, said cut-out portions provided with incline faces, whereby when one of said projections is placed in one of said cut-out portions, the frictional engagement between 65 the beveled end of said projection and the incline face of said cut-out portion will retain the same therein.

In testimony whereof I affix my signature in presence of two witnesses.

SAMUEL ARTHUR WELLS.
